CYLINDER HEAD

Application filed July 30, 1929. Serial No. 382,225.

This invention relates to cylinder heads for internal combustion engines, and while the improved construction is of general utility it is particularly applicable to air-cooled engines of the radial cylinder type such as are used in aviation.

It is the object of the invention to arrange the valves of an engine so as to provide for minimum over-all length of cylinder and at the same time insure proper cooling of the valves.

More particularly it is an object of the invention to provide the engine with a cylinder head of the side-valve or L type, with its valve chambers so positioned that movement of the aeroplane or other vehicle in which the engine is installed will circulate air completely around the valve chamber for properly cooling the valves.

The employment of L-head valves is particularly advantageous in aviation engines of the radial cylinder type in that an L-head construction reduces cylinder length as compared with overhead valves in order that the diameter of a radial cylinder engine may be appreciably reduced for decreasing wind resistance, and an L-head construction also assures greater accessibility and convenience for lubricating valve mechanism than is possible in a radial cylinder engine having overhead valves.

The invention utilizes these marked advantages of L-head valves and at the same time provides adequate heat radiating and cooling-medium circulating space around the valve chambers in order to adapt the construction for use in air-cooled engines such as radial cylinder aviation engines.

Further objects of the invention will be readily understood from the following description of the accompanying drawings, in which:

Fig. 1 is a fragmentary plan view of a radial cylinder aviation engine, showing one of the cylinders partly in section on the line 1—1 of Fig. 2.

Fig. 2 is a fragmentary front elevation of the engine, with one of the cylinders partly in section on the line 2—2 of Fig. 1.

Fig. 3 is a detail section on the line 3—3 of Fig. 1.

The invention is illustrated as embodied in an aviation engine in which cylinders 1 extend radially from a crank case 2 with the main shaft 3 for the propeller (not shown) projecting forwardly from the crank case.

The head of each cylinder is of the side-valve or L type as distinguished from an overhead-valve construction. As an instance of this arrangement the cylinder head comprises a closure plate 4 having a depending neck 5 which is preferably threaded onto cylinder 1 as shown at 6 so that the closure plate forms a combustion chamber 7 at the top of the cylinder. Axially extending valve chambers 8 for the intake and exhaust valves 9 are preferably cast integral with closure plate 4 at the periphery thereof, with the upper ends of the valve chambers preferably closed by usual threaded plugs 10 and communicating immediately below said closure plugs with the combustion chamber 7 via downwardly sloping passageways 11. Usual spark plugs 12 may be mounted in the wall of closure plate 4 in back of valve chambers 8 so that the spark plugs extend into the combustion chamber 7.

The valve chambers are arranged for maximum heat radiation and for circulation of a cooling-medium completely around the valve chambers, and for this purpose the pair of valve chambers for the intake and exhaust valves of a cylinder are preferably laterally spaced from one another at the front of the cylinder, with the depending portions of the valve chambers spaced radially outwardly from the neck 5 of closure plate 4. These depending portions of the valve chambers preferably terminate in outwardly and rearwardly inclined conduits 13 which are also spaced radially outwardly from neck 5 of closure plate 4, and the respective conduits 13 are connected to usual intake and exhaust pipes (not shown).

Usual seats 14 for the valves 9 are formed in chambers 8 immediately below passageways 11 so that the valve seats are at the upper ends of those depending portions of the valve chambers which are spaced radially

outwardly from neck 5, and usual stems 15 for the valves extend axially through the depending portions of the valve chambers and project downwardly therebeyond through 5 usual guide bosses 16, the valve stems being actuated by usual operating mechanism indicated generally at 17.

The entire outer circumferences of those outwardly radially spaced depending portions of the valve chambers in which the valvular structures are mounted are thus exposed for head radiation, and passageways 18 formed between the neck 5 and the outwardly radially spaced depending portions of the 15 valve chambers extend around back of said depending portions of the valve chambers and are open at their respective ends as a result of the lateral spacing of the pair of intake and exhaust valve chambers at the 20 front of a cylinder and the radial spacing of intake and exhaust conduits 13 from the neck 5 at the opposite ends of these passageways. When the aeroplane or other vehicle is in motion, rearwardly induced currents of air 25 are thus directed into the passageways 18 which open at the front of their cylinder, and air thus flows freely around back of the valve chambers 8 through said passageways as well as around the front circumferential 30 portions of the valve chambers, thereby insuring circulation of the cooling medium around the entire circumference of those depending portions of the valve chambers in which the valvular structures are mounted.

35 The cylinder 1 may be provided with usual fins 20, and the cylinder head is preferably also provided with heat radiating fins. Thus for example axially spaced fins 21 may extend around the neck 5 of the cylinder head and may be continued as fins 21^a extending across the passageways 18 and formed integral with the valve chambers 8 and the conduits 13, and upstanding laterally spaced fins 22 may extend fore-and-aft across the closure plate 4, with continuations 22^a of said fins preferably provided on the closure plugs 10. Axially spaced arcuate fins 23 may also extend around the outer peripheral portions of the upper ends of the chambers 8 which are cast integral with closure plate 4 at its periphery, with said arcuate fins preferably merging into the upstanding fins 22 at their respective ends.

The invention thus provides a cylinder head having side-valves whereby the valve mechanism instead of projecting axially beyond the cylinder is positioned axially below the cylinder head, thereby providing a construction particularly applicable to radial cylinder aviation engines where minimum over-all diameter for reducing wind resistance and accessibility of valve mechanism for lubrication are desiderata; and the provision of passageways 18 around back of the depending portions of chambers 8 in which the valvular structures are mounted, together with

the opening of said passageways at the front of the engine between the laterally spaced pair of valve chambers for the intake and exhaust valves of a cylinder, permits of such side-valve construction in an air-cooled engine with assurance of adequate cooling of the valves, since the entire circumferences of the depending portions of the valve chambers are exposed for heat radiation, and air circulation is induced through the passageways 18 and thus completely around the valve chambers when the aeroplane or other vehicle in which the engine is installed is in motion.

By incorporating the improved valvular construction in a radial multi-cylinder engine the valve chambers at the front of each of the cylinders are directly exposed to cooling air currents adapted for flow through the passageways 18 without the air currents for any one cylinder having been previously heated by flow past a preceding cylinder as would be the case with a multi-cylinder engine having its cylinders in alignment axially of the engine.

The invention also provides an extremely simple construction by casting the valve chambers integral with the cylinder head which is adapted for detachable mounting on its cylinder; and by inclining the conduits rearwardly as well as outwardly from valve chambers 8, the fins 21 are adapted to rigidly fix the valve chambers and conduits relative to their cylinder, with the passageways 18 merely of sufficient size to provide the desired air circulation.

I claim:

1. In a multi-cylinder internal combustion engine having its plurality of cylinders projecting radially from a common axis; a valve chamber for each of said cylinders communicating at its upper end with its cylinder and extending downwardly in radially spaced relation from its cylinder for exposing the entire circumferential outer surface of the depending portion of the valve chamber, the valve chamber being in front of its cylinder longitudinally of said common axis, and being laterally spaced to one side of that axial plane of its cylinder which extends longitudinally of said common axis.

2. In a multi-cylinder internal combustion engine having its plurality of cylinders projecting radially from a common axis; valve chambers for each of said cylinders communicating at their upper ends with their cylinder and extending downwardly in laterally spaced relation from one another and radially spaced relation from their cylinder for exposing the entire circumferential outer surfaces of the depending portions of said valve chambers, said valve chambers being in front of their cylinder longitudinally of said common axis.

3. In a multi-cylinder internal combustion

- engine having its plurality of cylinders projecting radially from a common axis; a valve chamber for each of said cylinders communicating at its upper end with its cylinder and extending downwardly in radially spaced relation from its cylinder for exposing the entire circumferential outer surface of the depending portion of said valve chamber, the said valve chamber being in front of its cylinder longitudinally of said common axis, and being laterally spaced to one side of that axial plane of its cylinder which extends longitudinally of said common axis, a conduit extending rearwardly from the depending portion of the valve chamber in radially spaced relation from its cylinder, and a fin projecting radially from the cylinder to both the rearwardly extending conduit and the depending portion of the valve chamber. 5
4. In combination, a cylinder for an internal combustion engine, a valve chamber communicating at its upper end with the cylinder and extending downwardly in radially spaced relation from the cylinder for exposing the entire circumferential outer surface of the depending portion of the valve chamber, the said valve chamber being in front of its cylinder longitudinally of said common axis, and being laterally spaced to one side of that axial plane of its cylinder which extends longitudinally of said common axis, a conduit extending rearwardly from the depending portion of the valve chamber in radially spaced relation from its cylinder. 10
5. In combination, a cylinder for an internal combustion engine, a head having a depending collar detachably mounted on the cylinder, the head including a valve chamber integral therewith and communicating at its upper end with the cylinder via said head and extending downwardly in radially spaced relation from the collar of the head for exposing the entire circumferential outer surface of the depending portion of said valve chamber, and a fin projecting radially from said collar to the depending portion of the valve chamber. 15
6. In combination, a cylinder for an internal combustion engine, a head having a depending collar detachably mounted on the cylinder, the head including a valve chamber integral therewith and communicating at its upper end with the cylinder via said head and extending downwardly in radially spaced relation from the collar of the head for exposing the entire circumferential outer surface of the depending portion of said valve chamber, a conduit extending laterally from the depending portion of the valve chamber alongside and in radially spaced relation from the said collar, and a fin projecting radially from said collar to both the conduit and the depending portion of the valve chamber. 20
7. In combination, a cylinder for an internal combustion engine, and a head for the cylinder, the head including a valve chamber integral therewith and forming a valve seat and communicating at its upper end with the cylinder via said head and extending downwardly with the entire portion of the valve chamber which is below the valve seat radially spaced from the cylinder for exposing the entire circumferential outer surface of the depending portion of said valve chamber. 25
8. In a multi-cylinder internal combustion engine having its plurality of cylinders projecting radially from a common axis; a valve chamber for each of said cylinders communicating at its upper end with its cylinder and extending downwardly in radially spaced relation from its cylinder for exposing the entire circumferential outer surface of the depending portion of said valve chamber, the said valve chamber being in front of its cylinder longitudinally of said common axis, and being laterally spaced to one side of that axial plane of its cylinder which extends longitudinally of said common axis, a conduit extending rearwardly from the depending portion of the valve chamber in radially spaced relation from its cylinder. 30
9. In combination, a cylinder for an internal combustion engine, a valve chamber communicating at its upper end with the cylinder and extending downwardly in radially spaced relation from the cylinder for exposing the entire circumferential outer surface of the depending portion of the valve chamber, and a conduit extending laterally from the depending portion of the valve chamber alongside and in restricted radially spaced relation from the cylinder. 35
10. In combination, a cylinder for an internal combustion engine, a head for the cylinder having a depending collar mounted on the cylinder, the head including a valve chamber integral therewith and communicating at its upper end with the cylinder via said head and extending downwardly in radially spaced relation from the collar of the head for exposing the entire circumferential outer surface of the depending portion of said valve chamber, and a fin projecting transversely from said collar to the depending portion of the valve chamber. 40
